FREDERICK C. AYLING, OF SYRACUSE, NEW YORK, ASSIGNOR TO UNITED SHOE MACHINERY CORPORATION, OF PATERSON, NEW JERSEY, A CORPORATION OF NEW JERSEY

SHOE AND SHANK PIECE AND METHOD OF MAKING SHOES

Application filed January 9, 1930. Serial No. 419,666.

This invention relates to improved devices for use in stiffening the shanks and bracing the heels of shoes and to improvements in shoes and methods of making the same. The present application is a continuation of my application for Letters Patent, Serial No. 335,569, filed January 29, 1929, as to all subject-matter that is common to the two applications. The invention is herein illustrated with reference to its application to shoes having high wood heels, although in various aspects the invention is useful also in connection with shoes having other types of heels.

In most shoes the longitudinally arched shank portion of the shoe bottom is supported and reinforced by means of a shank stiffener which usually extends from the vicinity of the ball line rearwardly to a point located above the heel but which has no direct connection with the heel itself. In women's shoes having high heels such shank stiffeners are ineffective to maintain the desired heightwise angular relation of the heel to the shank portion of the shoe bottom and there is liable to be relative tilting movement lengthwise of the shoe between the heel and sole while the shoe is being worn, with the result that the joint between the heel and sole at the top of the heel breast may open up and the heel become displaced from its proper relation to the shoe. Moreover, in a shoe having a high heel, there is liable to be relative movement lengthwise of the shoe between the shank stiffener and the heel with resulting displacement of the stiffener and distortion of the shoe.

In view of the foregoing, one object of the present invention is to provide improved means for supporting and reinforcing the shank portion of a shoe, and particularly of a woman's narrow shank and high heel shoe, which will also be capable of use in bracing the heel in such a manner as to insure against any displacement of the heel from its proper position relatively to the shoe and to prevent relative movement between the shank piece and the heel lengthwise of the shoe.

With this object in view, one feature of the invention consists in the provision of a shank piece comprising a longitudinally arched narrow strip of resilient metal adapted to lie

within the space between the opposite portions of the sewing rib or lasted-over margins of the upper materials along the shank portion of the bottom of a narrow shank shoe, and having an enlarged rear extremity adapted to fit between the lasted-over margins of the upper materials at the heel seat of the shoe, said enlarged portion having a centrally disposed circular hole of a diameter to receive a heel-attaching screw and to fit closely all around the shank portion of the screw to insure rigid connection between the shank piece and a heel attached to the shoe.

For use in welt shoes it is often advantageous to provide a shank piece of composite construction, such as illustrated herein, comprising a stiffener strip substantially like the metallic shank piece already described, and a filler piece which is secured to the stiffener member and has a hole in its rear portion coaxially aligned with the hole in the stiffener member for receiving the heel-attaching fastener. The circular heel-fastener-receiving hole in each of the shank pieces herein illustrated is of such diameter that the shank of an ordinary wood screw of a size suitable for use in attaching a heel to a shoe will fit snugly within the hole so that no movement of the shank piece lengthwise of the shoe and no relative tilting of the shank piece and heel will be possible after the screw has been driven into heel-attaching position. Thus, not only will the screw secure or assist in securing the heel to the shoe but, since the screw is removably connected with the shank piece, the latter, in conjunction with the screw, will serve as a combined shank stiffener and heel brace to prevent any tilting of the heel relatively to the shank piece and consequently the heel will be maintained in its proper angular relation to the shank portion of the shoe.

Invention accordingly is to be recognized as residing in the combination in a shoe having inner and outer soles, of a combined shank stiffener and heel brace comprising a longitudinally arched metallic strip and a filler piece, said strip having an enlarged rear portion provided with a hole, and said filler piece having a hole registering with the hole

in said strip and having a marginal contour adapted to fit between the upper materials along the opposite margins of the shank portion of the shoe bottom, a heel-attaching fastener extending through and fitting snugly within both said holes rigidly to anchor said strip to the heel of the shoe, and a plurality of heel-attaching nails extending through the shoe bottom and spaced outwardly from the 10 edge of said strip.

The invention further resides in an improvement in methods of making shoes having inner and outer soles which consists in assembling between the soles a shank piece 15 having a hole in its rear portion, positioning a heel upon the shoe, driving through both soles and through the hole in the shank piece and into the heel a screw of a size to fit tightly within the hole in the shank piece to secure 20 rigidly together the heel, the shank piece, and both soles of the shoe and thus to brace the heel and stiffen the shank portion of the shoe, and driving a plurality of heel-attaching 25 nails through said soles outside of the shank piece.

In employing a wood screw, such as that above referred to, for securing a heel to a shoe, the screw is inserted from the inside of the shoe. Accordingly, in order to insure 30 that the screw will pass through the insole of the shoe at such a location that it will be certain to enter the hole in the shank piece, the shank piece is accurately positioned with its fastener-receiving hole registering with 35 a hole previously formed in the insole and the shank piece is positively maintained in that position throughout all the making operations which take place between the laying of the shank piece and the final insertion of 40 the heel-attaching screw or fastener. In another aspect therefore the invention further resides in an improvement in methods of making shoes of the type wherein a shank piece extends rearwardly above the heel and 45 has a heel-fastener-receiving hole formed therein which consists in assembling an insole and an upper, boring a hole through the heel portion of the insole, positioning a shank piece against the outer face of the insole 50 with the hole in the shank piece in substantially coaxial relation to the hole in the insole and securing the shank piece to the insole, attaching an outsole and a heel to the shoe, and thereafter passing a fastener 55 through the holes in the insole and shank piece and through the outsole and into the heel to anchor the shank piece and permanently attach the heel to the shoe.

As herein exemplified, a temporary locating device in the form of a wooden peg is employed for positioning the shank piece and for maintaining it in position during subsequent shoemaking operations. This wooden peg is inserted through the holes in the shank piece and insole and is removed be-

fore the heel-attaching screw is inserted. If desired the shank piece may be manufactured with the locating peg assembled therewith and accordingly invention is also to be recognized in a shank piece formed with an 70 apertured rear portion and having a removable locating member temporarily secured within the aperture in the shank piece.

In the practice of my improved method, as herein exemplified in the manufacture of welt shoes, the shoe is made on a last of the type disclosed in United States Letters Patent No. 1,615,258, granted January 25, 1927, upon application of Maurice V. Bresnahan, such a last having a hole extending from the top to the bottom of its heel portion to permit the passage through the last of a drill for boring through the heel seat portion of the shoe and into a heel on the shoe preparatory to the driving of a screw through the shoe bottom 85 and into the heel after the upper materials and the insole have been assembled on the last, and the pulling over, lasting and inseaming operations have been performed in the manner customary in the manufacture of welt 90 shoes, a drill is passed through the hole in the last and operated to bore a hole through the insole in line with the hole in the last. Thereafter, as herein exemplified, the following 95 operations take place; the shank piece is laid against the insole and positioned with its fastener-receiving hole in alignment with the hole in the insole by means of a tapered wooden peg which is passed through the hole 100 in the shank piece and into the holes in the insole and last; an outsole is laid and heel-seat-fitted; a heel is positioned upon the heel seat and temporarily clamped in place (suitable adhesive having been employed between 105 the heel and the shoe); the drill is again inserted in the hole in the last and is passed downwardly through the insole, shank piece and outsole and into the heel, the drill passing 110 through the previously formed hole in the insole and the aligned hole in the shank piece and operating to drill out the wooden peg and to form holes in the outsole and heel which are in line with each other and also with the holes in the insole and the last. After the adhesive 115 between the heel and the shoe has become set the last is pulled, and an ordinary wood screw is inserted from the inside of the shoe, the screw passing through the aligned holes in the insole, shank stiffener and outsole and into 120 the hole in the heel and the screw functioning to hold both the heel and the shank piece securely in place and serving, in conjunction with the shank piece, as a heel brace to prevent any tipping of the heel and opening up of the joint between the heel and the sole at the top of the heel breast.

The invention will be explained with reference to the accompanying drawings, in which Fig. 1 is a perspective view of an improved 125

shank piece constructed in accordance with the present invention;

Fig. 2 is a sectional view taken along the line II—II of Fig. 1 and showing also a locating peg extending through the fastener-receiving hole in the rear portion of the shank piece;

Fig. 3 is a perspective view of an alternative form of shank piece hereinafter described;

Fig. 4 is a sectional view taken along the line IV—IV of Fig. 3;

Fig. 5 is a sectional view taken along the line V—V of Fig. 3;

Fig. 6 is a side elevational view of a shoe mounted on a last, portions of the shoe and last being broken away to disclose the manner of positioning the shank piece relatively to the insole of the shoe;

Fig. 7 is a view similar to Fig. 6 but showing the shoe as it appears after the outsole has been laid and a heel has been applied and clamped in place by means of a temporary wood heel-attaching screw;

Fig. 8 is a side elevational view of the shoe as it appears after the last has been removed and the heel permanently secured in place, the shoe being broken away to disclose the construction and arrangement of the shank piece and the heel-attaching screw; and

Fig. 9 is a sectional view taken along the line IX—IX of Fig. 8.

Referring first to Figs. 1 and 2 of the drawings, the shank piece 10 therein shown consists of a resilient strip of tempered metal comprising an elongated narrow portion 12 adapted to extend along the shank portion of a shoe, and an enlarged or relatively wide portion 14 adapted to be located above the heel of the shoe. The narrow portion 12 is longitudinally arched to correspond to the longitudinal arch of the shank portion of the last for a shoe in which the shank piece is to be incorporated and this narrow portion 45 of the device is reinforced by means of a longitudinal stiffening rib 16 which is centrally disposed widthwise of the strip and projects from the longitudinally concave or outsole-engaging side of the strip. The width of the elongated narrow portion of the shank piece 10 is such as to adapt it to fit within the narrow space between the portions of the sewing rib or lasted-over upper margins which extend along the opposite sides of the shank portion of insoles for women's narrow shank shoes. The flat rear portion 14 of the shank piece 10 is provided with a centrally disposed circular hole 18 for receiving a screw which is to function both as a permanent heel-attaching fastener and as a means for anchoring the shank piece and also, in conjunction with the shank piece itself, as a heel brace to hold the heel against displacement relatively to the shoe. The circular hole 18 is made of a diameter to fit

closely all the way around the shank. The enlarged portion 14 is wide enough effectively to brace the stiffener against torsional displacement and thus to prevent twisting of the shank portion of the shoe but not so large as to interfere with the use of heel attaching nails in the locations in the heel seat of the shoe in which they are usually driven. As shown, two tack holes 20 are provided in the portion 12 of the shank piece through which tacks may be driven, if desired, to secure the shank piece to the insole of the shoe.

In Figs. 3, 4 and 5 there is shown an alternative form of shank piece which is of composite construction comprising a stiffener member 100 and a filler piece 102, the latter being secured to the former by means of tacks 104 which extend through tack holes in the stiffener member 100. The stiffener member 100 is made of tempered metal and is substantially like the device shown in Figs. 1 and 2 and already described, the member 100 having an enlarged flat rear portion 140, a stiffening rib 160, and a heel-

fastener-receiving hole 180 of a diameter to fit snugly the shank portion of a heel-attaching screw. The filler piece 102 which may be formed of leather, leatherboard, or other suitable material, is made of a thickness sufficient to fill the space between the soles of the shoe and has a marginal contour adapted to fit between the inseamed materials along the opposite margins of the shank portion of the shoe bottom. As shown in Fig. 5, the filler piece 102 is transversely curved or molded to provide a trough-like depression 184, co-extensive with the stiffening rib 160, for receiving the latter and to provide a desired transverse convexity at the outsole-engaging side of the stiffener. A hole 182 (Fig. 4) is provided in the rear portion of the filler piece 102, in alignment with the hole 180 in the stiffener member 100, for receiving the heel-attaching screw which is to extend also through the hole 180 in the stiffener member. The holes 180 and 182 in the composite shank piece just described, and the hole 18 in the shank piece 10 shown in Figs. 1 and 2, are also adapted to receive a locating peg or plug, such as the peg 186 shown in Figs. 2 and 6, the peg 186 being temporarily employed during the process of manufacturing a shoe for the purpose of positioning the shank piece to receive the heel-attaching screw, as will be hereinafter explained in detail.

In order that the shank piece shall be positioned and secured in the shoe so that it will properly perform its intended function, the shoe in which it is to be incorporated is made, and the shank piece is assembled therewith, in accordance with an improved method of shoemaking which, as herein exemplified in the manufacture of

welt shoes, involves the use of a last A (Fig. 6) of the type disclosed in Letters Patent No. 1,615,258, hereinbefore referred to, such a last having a hole B extending therethrough from its cone to its heel seat surface to permit drilling operations to be performed in the soles and heel of the shoe without removing the last, and also to permit the use of a screw fastener for temporarily securing together the heel, the shoe, and the last prior to the permanent attachment of the heel to the shoe.

The operations involved in the practice of the illustrative method will now be described.

18 An insole C having been secured to the bottom of the last A (Fig. 6) as by means of tacks in the customary manner, the upper materials D are assembled on the last, pulled over and lasted to the insole in the usual way.

20 A hole E is then made through the insole, in alignment with the hole B in the last, by means of a suitable tool, such as a drill (not shown) which is passed downwardly through the hole B in the last. A shank piece, herein

25 shown as the shank piece 10, is next laid against the outer face of the insole C with its fastener-receiving hole 18 alined with the hole E in the insole and the hole B in the last, this being accomplished, as herein ex-

30 emplified, by the use of the locating peg 186 which, for this purpose, is passed through the holes in the shank piece and insole and projected into the hole in the last. Conveniently, the locating peg 186 may initially be 35 driven through the hole in the shank piece a sufficient distance to cause it to become wedged or frictionally engaged therein before the shank piece is laid against the insole, in which case the peg will serve to position

40 the shank piece with its hole 18 in registry with the holes in the insole and last as well as thereafter to maintain the shank piece in that position. In practice it may be found convenient to assemble the pegs in the holes

45 in the shank pieces before the shank pieces are shipped to the manufacturers who are to use them in the making of shoes. If desired, however, the shank pieces and the locating pegs may be shipped separately and assem-

50 bled by the shoe manufacturer either before or after the shank piece has been applied to the shoe. If the shank piece is to be laid in place against the insole before the peg is inserted in the hole in the shank piece, the hole

55 18 in the shank piece should first be registered approximately with the hole in the insole by the eye of the operator, after which the locating peg 186 may be driven through the shank piece and into the holes in the insole and last.

60 In any case the peg 186 is finally positioned with its larger end substantially flush with the outer surface of the shank piece, as shown in Fig. 6. On account of the wedged or tapered formation of the peg, the peg will 65 thus be cramped within the hole in the shank

piece and it will positively hold the shank piece in place with the hole 18 registering with the holes in the insole and last.

The shank piece having been positioned relatively to the insole and last, as above described, an outsole F is laid, rough-trimmed and channeled, stitched to the welt, leveled, and heel-seat-fitted, all in the customary manner, the peg 186 functioning during all these operations positively to maintain the shank piece in place with its hole 18 in registry with the holes in the insole and last. The peg 186 is particularly useful during the leveling operation inasmuch as the peg functions then to prevent any displacement of the soles and the shank piece crosswise of the shoe such as would otherwise be liable to occur as a result of the action of the pressure roll in leveling machines of the type commonly used to level the bottoms of welt shoes.

70 The shoe is now ready to have a heel, such as the wood heel G (Figs. 7 and 8), attached thereto. After adhesive has been applied to the heel seat of the shoe, or to the seat face of the heel, or to each of these surfaces, the heel G is placed in position upon the shoe and temporarily clamped thereon by means not herein shown. Any suitable clamping device may be used for this purpose but preferably a device is employed, such as that shown in United States Letters Patent No. 1,722,992, granted August 6, 1929, upon application of F. E. Bertrand, the machine shown in this patent being adapted also to 75 perform the drilling and certain other operations hereinafter to be described.

75 After the heel has been temporarily clamped to the shoe a drill (not shown) is passed downwardly through the hole B in the last and operated to drill out the locating

80 peg 186 and to pass downwardly through the hole E in the insole C and through the hole 18 in the shank piece 10 to form a hole H (Figs. 7 and 8) through the outsole F and to bore a hole or socket I in the heel G, the

85 holes H and I being made in coaxial alignment with the holes in the shank piece, insole and last. Upon the removal of the drill from the last a temporary heel clamping

90 device in the form of an elongated screw J (Fig. 7) is employed, in accordance with the method herein exemplified, the screw J being passed through the hole in the last and downwardly through the holes in the insole, shank piece and outsole and rotated into

95 holding engagement with the walls of the hole I in the heel. A temporary clamping screw of this type is disclosed in the Bresnahan Patent No. 1,615,258, already referred to and, as described therein, such a screw

100 serves to hold the heel in place during the setting of the adhesive at the heel seat and permits the clamp originally employed for holding the heel to the shoe to be released, thus enabling the shoe to be passed along

through the shoe factory for the performance of various finishing operations thereon.

When sufficient time has elapsed for the setting of the adhesive at the heel seat, the temporary clamping screw J is removed, the last A is pulled, and a permanent heel-attaching fastening in the form of an ordinary wood screw K (Fig. 8) is inserted from the inside of the shoe, the screw K passing downwardly through the hole E in the insole, the hole 18 in the shank piece, the hole H in the outsole and into the hole I in the heel. The screw K is driven or turned until holding engagement is secured with the wood of the heel and the beveled head of the screw has been countersunk in the insole so that the upper surface of the screw head is flush with the inner surface of the insole, as shown in Fig. 8. The usual heel-attaching nails (indicated at L in Figs. 8 and 9) may also be driven through both soles and into the heel, the rear portion of the shank piece being so shaped and arranged that it will not interfere with the driving of these nails in the usual locations.

Inasmuch as the shank of the screw K fits snugly within the hole 18 in the shank piece 10, and inasmuch as the shank piece 10, the soles C and F, and the heel G are all rigidly secured together, there can be no relative tipping of the heel and the shoe in directions lengthwise of the shoe, such as would tend to cause the joint between the breast of the heel and the outsole to open up, and consequently the desired angular relation between the heel and the shank portion of the shoe is insured throughout the life of the shoe. Moreover, there can be no relative shifting movement lengthwise of the shoe between the shank piece and the heel and thus the shank piece is permanently secured in such relation lengthwise of the shoe as to maintain the longitudinal arch in the shank portion of the shoe in conformity with the corresponding arch of the last upon which the shoe is made. Thus, by the combined action of the shank piece 10 and the screw K the shank piece is enabled more effectively to support and stiffen the shank portion of the shoe while the screw K is enabled more securely to hold the heel in place.

While the shank piece 10 shown in Figs. 1 and 2 has been herein described in connection with its application to a welt shoe, this particular form of shank piece is well adapted also for use in McKay-sewed shoes or other shoes in which the upper is directly secured to the tread sole as, for example, shoes in which the tread sole is attached by cement. When used in the manufacture of McKay-sewed shoes it may be found desirable to employ, in connection with the shank piece, a locating peg which is short enough so that it will not project beyond substantially the inner surface of the insole. While

such a peg will not function to hold the shank piece and insole in a definite relation to a last or form during the sole leveling operation such action is not essential in the manufacture of McKay-sewed shoes inasmuch as the pressure applied during the leveling of such shoes is direct pressure and consequently there is little, if any, tendency for the shoe bottom as a whole to be displaced laterally with respect to the last or form within the shoe.

The composite shank piece shown in Figs. 3, 4 and 5, being provided with a filler member, is particularly adapted for use in welt shoes wherein the filler piece serves to fill the space between the soles, thus avoiding the necessity of subsequently applying plastic filler or the like to the shank portion of the shoe, while the marginal outline of the filler piece is such as to conform to the contour of the portions of the sewing rib at the opposite sides of the shoe. As shown in Fig. 4, the hole 182 in the filler piece 102 may advantageously be made somewhat smaller than the hole 180 in the stiffener member 100. Because of the yielding character of the material of the filler piece, such a construction will provide for a more effective wedging or cramping of the locating peg in the shank piece while still providing for a snug fit between the shank of the screw and the edge of the hole in the stiffener member.

Having described my invention, what I claim as new and desire to secure by Letters Patent of the United States is:

1. A shank piece comprising a longitudinally arched narrow strip of resilient metal adapted to lie within the space between the lasted-over margins of the upper materials along the shank portion of the bottom of a narrow shank shoe, and having an enlarged rear extremity adapted to fit between the lasted-over margins of the upper materials at the heel seat of the shoe, said enlarged portion having a centrally disposed circular hole of a diameter to receive a heel-attaching screw and to fit closely all around the shank portion of the screw to insure rigid connection between the shank piece and a heel attached to the shoe.

2. A shank piece comprising a strip of tempered metal having a relatively narrow longitudinally arched portion of uniform width adapted to extend along the shank portion of the bottom of a shoe, and a flat and relatively wide rear portion adapted to extend above the attaching face of the heel of the shoe, said narrow portion being reinforced by a centrally disposed longitudinal stiffening rib, and said rear portion being shaped to avoid interference with heel-attaching nails and having a centrally disposed circular hole of a size to receive and have tight fitting engagement with the shank of a heel-attaching screw.

3. As an article of manufacture, a shank piece formed with an apertured rear portion and having a removable locating member temporarily secured within the aperture in the shank piece in position for use in locating the shank piece relatively to a hole in the bottom of a shoe. 70
4. As an article of manufacture, a shank piece having an apertured rear portion adapted to extend above the heel of a shoe and having a tapered locating peg secured in assembled relation therewith prior to the application of the shank piece to the shoe, said peg being wedged in the aperture in the rear portion of the shank piece and projecting beyond the insole-engaging side of the shank piece to locate the latter prior to its attachment to the shoe. 75
5. A composite shank piece comprising a longitudinally arched stiffener strip adapted to extend rearwardly above the attaching face of the heel of a shoe and having a hole in its rear portion for receiving a heel-attaching fastener, and a filler piece secured to the stiffener strip and having a hole in its rear portion of smaller diameter than the hole in the stiffener strip and axially aligned with the hole in the stiffener strip. 80
6. A composite shank piece comprising a longitudinally arched stiffener strip formed with a longitudinal reinforcing rib upon its longitudinally concave side and having a flat enlarged rear portion adapted to extend above the attaching face of the heel of a shoe, and a filler member coextensive with the stiffener member and secured to the ribbed side thereof, the filler member being transversely concave throughout a portion of its length to receive the rib of the stiffener strip, said stiffener strip and filled piece having registering holes in their rear portions for receiving a heel-attaching fastening. 85
7. In a shoe having inner and outer soles, a combined shank stiffener and heel brace comprising a longitudinally arched strip having an enlarged and apertured rear portion extending above the attaching face of the heel of the shoe, said enlarged portion being shaped and arranged to avoid interference with heel-attaching nails driven in the usual locations in the heel seat of the shoe, a heel-attaching fastening extending through the aperture in said strip and tightly fitting within said aperture to prevent relative bodily movement between said strip and the heel, and a plurality of heel-attaching nails extending through the bottom of the shoe outside of the stiffener. 90
8. A shoe having a wooden heel, an innersole and a shank piece both extending along the arch and over the heel, fasteners extending through the innersole into the heel outside of the shank piece, an additional fastener extending through registering aper- 95
- tures in the innersole and shank piece and into the heel, the last-named fastener filling the aperture in the shank piece to hold the shank piece and the fastener against relative movement lengthwise of the shank piece, and a plurality of nails extending through the shoe bottom and into the heel in locations spaced outwardly from the edge of the shank piece. 100
9. In a double-soled shoe having lasted-over upper margins between the soles, a composite shank piece located between the soles and within the space between the lasted-over upper margins, said shank piece comprising a narrow stiffener strip and a filler member, said stiffener strip being longitudinally arched and having a fastener-receiving hole in its rear portion located above the attaching face of the heel of the shoe, and said filler member being coextensive with the stiffener strip and having a fastener-receiving hole registering with the hole in the stiffener strip, and a heel-attaching fastener extending through and tightly fitting within the holes in the stiffener strip and filler member and extending through both the insole and outsole and having holding engagement with the heel. 105
10. In a shoe having inner and outer soles, a combined shank stiffener and heel brace of composite construction located between the soles and comprising a longitudinally arched metallic strip and a filler piece, said strip having an enlarged rear portion provided with a hole, and said filler piece having a hole registering with the hole in said strip, and having a marginal contour adapted to fit between the upper materials along the opposite margins of the shank portion of the shoe bottom, a heel-attaching fastener extending through and fitting snugly within both said holes rigidly to anchor said strip to the heel of the shoe, and a plurality of heel-attaching nails extending through the shoe bottom and spaced outwardly from the edge of said strip. 110
11. That improvement in methods of making shoes having innersoles which consists in assembling between the inner and outer soles a shank piece having a hole in its rear portion, positioning a heel upon the shoe, driving through both soles and through the hole in the shank piece and into the heel a screw of a size to fit tightly within the hole in the shank piece to secure rigidly together the heel and the shank piece and both soles of the shoe and thus to brace the heel and stiffen the shank portion of the shoe, and driving a plurality of heel-attaching nails through said soles outside of the shank piece. 115
12. That improvement in methods of making shoes which consists in placing against the outer side of the innersole of a shoe a shank piece having a fastener-receiving hole 120
13. That improvement in methods of making shoes having innersoles which consists in assembling between the inner and outer soles a shank piece having a hole in its rear portion, positioning a heel upon the shoe, driving through both soles and through the hole in the shank piece and into the heel a screw of a size to fit tightly within the hole in the shank piece to secure rigidly together the heel and the shank piece and both soles of the shoe and thus to brace the heel and stiffen the shank portion of the shoe, and driving a plurality of heel-attaching nails through said soles outside of the shank piece. 125

- in its rear portion and positioning the shank piece so that the hole will be located above the attaching face of a heel to be attached to the shoe, inserting a locating peg through 5 registering holes in the shank stiffener and the innersole to maintain said parts temporarily in place, clamping a wood heel to the shoe, removing the locating peg, and passing a fastener through said registering holes 10 and through the outsole and into the heel to fasten the heel rigidly and permanently to the shoe.
13. That improvement in methods of making shoes of the type wherein a shank piece 15 extends rearwardly above the heel and has a heel-fastener-receiving hole formed therein, which consists in assembling an insole and an upper, boring a hole through the heel portion of the insole, laying a shank piece 20 against the outer face of the insole, inserting a locating device in the holes in the shank piece and insole to position and maintain said parts with said holes in registration, laying an outsole and attaching its forepart and 25 shank portions to the upper, positioning a heel on the shoe, removing the locating device, boring holes through the outsole and into the heel in alinement with the holes in the insole and shank piece, and passing a 30 fastener through the holes in the insole, shank piece, outsole and heel to anchor the shank piece and permanently attach the heel to the shoe.
14. That improvement in methods of making 35 shoes of the type wherein a shank piece extends rearwardly above the heel and has a heel-fastener-receiving hole formed therein, which consists in assembling an insole and an upper, boring a hole through the heel 40 portion of the insole, laying a shank piece against the outer face of the insole, inserting a locating peg in the holes in the shank piece and insole to position and maintain said parts with said holes in registration, attaching an outsole, positioning a heel on the shoe, drilling downwardly through the holes in the insole and shank piece to remove the locating peg and to bore holes through the outsole and into the heel, and passing a 45 fastener through all of said holes to anchor the shank piece to the heel and permanently to attach the heel to the shoe.
15. That improvement in methods of making 50 shoes of the type wherein a shank piece extends rearwardly above the heel and has a heel-fastener-receiving hole formed therein, which consists in assembling an insole and an upper on a last having a hole extending therethrough from its cone to its heel-seat surface, boring a hole in the insole through the hole in the last, laying a shank piece upon the insole, passing a locating member through the hole in the shank piece and into the hole in the last to position the 55 shank piece in a predetermined relation to the insole, laying an outsole, positioning a heel upon the shoe, removing the locating member through the hole in the last, pulling the last, and passing a fastener through the hole in the insole and the hole in the shank piece and through the outsole and into the heel to anchor the shank piece and attach the heel to the shoe.
16. That improvement in methods of making 60 shoes of the type wherein a shank piece extends rearwardly above the heel and has a heel-fastener-receiving hole formed therein, which consists in tacking an insole to a last having a hole extending therethrough from its cone to its heel-seat surface, laying an upper over the insole, boring a hole in the insole through the hole in the last, laying a shank piece upon the outer face of the insole, passing a locating peg through the hole in the shank piece and through the hole in the insole and into the hole in the last to position and maintain the shank piece, insole and last with said holes in alinement, attaching and leveling an outsole, positioning a heel upon the shoe, operating a drill through the holes in the last, insole and shank piece to bore out the locating peg and to bore a hole through the outsole and into the heel, pulling the last, and inserting a wood screw through the holes in the insole, shank piece and outsole and into the hole in the heel to anchor the shank piece and attach the heel to the shoe.
17. That improvement in methods of making 65 shoes of the type having incorporated therein a combination shank stiffener and heel brace provided with a heel-fastener-receiving hole, which consists in assembling an insole and an upper, boring a hole through the heel portion of the insole, laying a shank stiffener against the outer face of the insole, inserting a locating device in the holes in the shank stiffener and insole to position and maintain said parts with said holes in registration, laying an outsole, positioning a heel on the shoe, removing said locating device, and passing a fastener through the holes in the insole and shank stiffener and through the outsole and into the heel to anchor the shank stiffener and permanently to attach and brace the heel.
18. That improvement in methods of making 70 shoes having inner soles which consists in placing a metal shank stiffener against the outer side of the innersole so that it extends rearwardly beyond the location of the breast of a heel to be attached to the shoe, inserting a wooden peg through registering holes in the innersole and the metal shank stiffener temporarily to maintain said parts in position, applying an outersole to extend across the outer side of the shank stiffener, placing a wooden heel in position against the outer side of the outersole, then removing the wooden peg and passing a fastener through 75

the registering holes in the innersole, the metal shank stiffener, and the outersole, and inserting the fastener into a socket in the heel rigidly and permanently to maintain the 5 parts in position.

19. That improvement in methods of making shoes of the type wherein a shank piece extends rearwardly above the heel and has a heel-fastener-receiving hole formed therein 10 which consists in assembling an insole and an upper, boring a hole through the heel portion of the insole, positioning a shank piece against the outer face of the insole with the hole in the shank piece in substantially coaxial relation to the hole in the insole and securing the shank piece to the insole, attaching an outsole and clamping a heel to the shoe, and thereafter passing a fastener through the holes in the insole and shank 15 piece and through the outsole and into the heel to anchor the shank piece and permanently attach the heel to the shoe.

20. That improvement in methods of making shoes of the type wherein a shank piece 20 extends rearwardly above the heel and has a heel-fastener-receiving hole formed therein which consists in positioning an insole upon the bottom of a last having a hole extending through the last from its cone to its heel seat 25 surface, lasting an upper and securing the upper to the insole, passing a boring tool through the hole in the last and operating the tool to bore a hole in the insole, positioning a shank piece upon the insole with the hole in the shank piece in substantially coaxial relation to the hole in the insole, attaching an outsole and clamping a heel to the shoe, passing a boring tool through the holes in the last, 30 insole and shank piece and operating the tool to bore a hole through the outsole and into the heel, withdrawing the boring tool, passing a screw fastener through the hole in the last and through the holes in the insole, shank piece and outsole and into the heel temporarily to secure said parts together, withdrawing said screw fastener, pulling the last and passing a wood screw through the holes in the insole, shank piece and outsole and into the hole in the heel, and driving the 35 screw into holding engagement with the heel 40 permanently to secure the heel to the shoe.

21. That improvement in methods of making shoes which consists in assembling together an insole, an upper, and a shank piece 45 having a heel-fastener-receiving hole therein and introducing removable means into the hole in the shank piece for locating the shank piece relatively to the insole, laying an outsole, and subsequently removing said locating means and attaching a heel by a fastener extending through the soles and through the 50 hole in the shank piece.

In testimony whereof I have signed my name to this specification.

60 FREDERICK C. AYLING.
